UNITED STATES PATENT OFFICE.

JOHN KETTEMAN, OF TOLEDO, OHIO.

DETACHABLE SHELF-BRACKET.

No. 798,683.

Specification of Letters Patent.

Patented Sept. 5, 1905.

Application filed September 16, 1904. Serial No. 224,661.

To all whom it may concern:

Be it known that I, JOHN KETTEMAN, of Toledo, county of Lucas, and State of Ohio, have invented certain new and useful Improvements 5 in Detachable Shelf-Brackets; and I do hereby declare that the following is a full, clear, and exact description of the invention, which will enable others skilled in the art to which it appertains to make and use the same, reference being had to the accompanying drawings, and to the characters of reference marked thereon, which form part of this specification.

My invention has reference to a detachable shelf-bracket; and it has for its object to provide a simple, inexpensive, and durable sheet-metal support for a shelf capable of convenient and instant attachment or detachment from a window-sill or other place where it may be employed.

20 In carrying out my invention I employ the novel combination and arrangement of the parts hereinafter shown, described, and claimed.

25 In the accompanying drawings, Figure 1 is a perspective view showing a shelf detachably mounted upon a window-sill, the same embodying my invention. Fig. 2 is a sectional elevation illustrating in dotted lines the operation for detaching the shelf. Fig. 3 is also 30 a sectional elevation showing a slightly-modified form of attaching-plate, the same being adapted for employment upon porches or other places where the attaching-plate may be secured by means of screws.

35 In the preferred embodiment of my invention I employ a bracket stamped out of sheet metal having a triangular-shaped body 1, the central portion thereof being cut out, as indicated at 2. The forward inclined edge portion 3 and the top edge portion 4 of the body are bent sharply at a right angle to stiffen and strengthen the same, providing an extremely-rigid support for the shelf 6, the portion 4 being provided with perforations to permit of fastening the shelf to the bracket by means of 45 screws, and the lower end of the portion 3 is extended at 6' to contact with the wall below the shelf when the latter is in position and provide a firm support for the same. The

50 extended portion 6' being of sheet metal not strengthened by ribs or otherwise, may be readily bent to adjust the shelf in true horizontal position. The portion 4 is also extended rearwardly, as at 5', and the extreme end is bent, as indicated at 7, to enter and engage one of a plurality of spaced transverse slots 8,

provided in a fastening-plate 9, also constructed of sheet metal, the side margins of which are bent downwardly, as at 10, to raise the central portion in which the slots are formed 60 above the window-sill, thereby permitting the convenient insertion of the bent end 7 of the extended portion 4 of the bracket. The fastening-plate at its outer end 11 is bent downwardly at a right angle, taking a position 65 when placed upon the window-sill between the outer face of the sill and the sash. The bent portion 11 at its lower margin is provided with serrations 12, extending inwardly to enter the sill, being forced into the same by the sash as 70 the latter is lowered. It will thus be seen that the fastening-plate is firmly secured in place without the employment of screws or other fastening devices which would mar the finish of the sill exposed to view when the 75 plate is detached. To cause the top surface of the shelf when in position upon the brackets to lie in the same plane with the window-sill, the rearwardly-extended portion 5' of the bracket is offset, as shown at 13, the window-sill being firmly clamped when the bracket is in position between said offset portion and the serrated portion of the fastening-plate.

80 The operation necessary to fasten the bracket in position is plainly indicated in Fig. 2. The slotted fastening-plate is first placed in position upon the window-sill and the bracket is then held in angular position with relation thereto, as indicated in dotted lines 90 a, to permit the insertion of the bent end of the extended portion 5' into one of the slots in the fastening-plate. Upon lowering the bracket to the position shown in full lines, Fig. 2, the same will be firmly held in place. 95

In Fig. 3 is shown a construction adapting the employment of my improved bracket upon porches or other like places, the slotted fastening-plate being secured by means of screws, the bracket being detachably engaged in the 100 same manner as herein described.

From the foregoing description the novelty, utility, and many advantages of my invention will be apparent.

Having described my invention, what I 105 claim, and desire to secure by Letters Patent, is—

1. In an article of the class described, a sheet-metal bracket having the top marginal edge portion thereof bent angularly and having said bent portion extended rearwardly and bent at the end, and a slotted plate adapt-

ed to be engaged by said extended portion, substantially as described.

2. In a device of the class described, a sheet-metal bracket having a triangular-shaped body, the forward and top marginal edges of which are bent angularly thereto, the said top angular portion being extended rearwardly and bent at the end, and a slotted sheet-metal plate adapted to be engaged by the bent end 5 of the extended portion of the bracket, substantially as described.

3. In a device of the class described, a sheet-metal bracket having the top and forward marginal edge portions thereof bent angularly and 10 having the top angular portion extended and bent at the end and provided with an offset 15

adjacent to the body of the bracket, and a sheet-metal plate provided with a plurality of spaced transverse slots adapted to be engaged by the extended portion of the bracket, said 20 plate being bent angularly at its outer end and provided with serrations along the lower margin of said angular portion, substantially as described.

In testimony that I claim the foregoing as 25 my own I affix my signature in presence of two witnesses.

JOHN KETTEMAN.
